MACHINE FOR PACKAGING GUM

John Van Buren, Brooklyn, N. Y.

Application April 2, 1941, Serial No. 386,420

6 Claims. (Cl. 93—2)

This invention relates to a machine for packaging gum. More particularly stated, the invention relates to a machine for alining and feeding a plurality of superposed pairs of sticks of gum and the invention has for its salient object to provide a machine of this character that is simple and practical in construction and is so constructed and arranged that the sticks will be neatly wrapped and the wrapper will be correctly positioned thereon.

Further objects of the invention will appear from the following specification taken in connection with the drawings which form a part of this application, and in which

Fig. 1 is a top plan view of the machine constructed in accordance with the invention;

Fig. 2 is a front elevation of the machine shown in Fig. 1;

Fig. 2A is a detail sectional elevation of the feed bar mechanism;

Fig. 3 is a detail sectional elevation taken substantially on line 3—3 of Fig. 4 showing differential gearing used in connection with the adjustment of the paper feed rolls;

Fig. 4 is a sectional elevation taken at right angles to Fig. 3;

Fig. 5 is an end elevation of the left hand end of the machine shown in Fig. 1;

Fig. 6 is a top plan view on an enlarged scale of the wrapper used for wrapping the gum;

Fig. 7 is a rear elevation of the machine shown in Fig. 1;

Fig. 8 is an end elevation of the machine shown in Fig. 1 looking at the right hand end of the machine;

Fig. 9 is a plan view on an enlarged scale and partly in section showing the central portion of the machine, including the feed pocket, plunger for feeding the sticks into the pocket and the correlated parts;

Fig. 10 is a vertical sectional elevation taken substantially on line 10—10 of Fig. 9;

Fig. 11 is a vertical sectional elevation on an enlarged scale taken through the paper feeding mechanism, package receiving pocket and correlated parts;

Fig. 12 is a sectional elevation of the discharge end of the second feed carrier which carries the gum through the end folding mechanism to the stacker;

Figs. 13 and 14 are sectional elevations taken substantially on lines 13—13 and 14—14 of Fig. 12;

Fig. 13A is a sectional elevation taken substantially on line 13A—13A of Fig. 13;

Fig. 15 is a sectional elevation of the control for the electric eye taken substantially on line 15—15 of Fig. 16;

Fig. 16 is a sectional elevation of the structure shown in Fig. 15 taken at right angles thereto;

Fig. 17 is an enlarged plan view illustrating the correction mechanism for coacting with the electric eye to correct the feed of the paper;

Fig. 18 is a view taken at right angles to Fig. 17;

Fig. 19 is a sectional elevation taken substantially on line 19—19 of Fig. 18;

Figs. 20 and 21 are sectional elevations illustrating two positions of the solenoid controlled member and the parts coacting therewith to turn the feed roll through an increment of movement to correct the feeding operation, these parts being shown in Fig. 20 in coacting position and in Fig. 21 in non-operative position;

Fig. 22 is a horizontal section of the pocket which receives the wrapper and plurality of sets of gum sticks;

Fig. 23 is an enlarged sectional elevation of the pocket and the moistener and end folder;

Fig. 24 is a sectional elevation taken through the side flap moistener substantially on line 24—24 of Fig. 9, this view being shown on an enlarged scale;

Fig. 25 is a diagrammatic view illustrating the circuit for the photo-electric cell; and

Fig. 26 is a perspective view of the completed package.

The invention briefly described consists of a simple and practical machine including means for feeding a plurality of superposed pairs of sticks of gum from a hopper to a wrapper, the wrapper being positioned in the path of movement of the plurality of pairs of superposed sticks, means for folding the wrapper around the gum

and securing the ends together and means operative thereafter to feed the wrapped gum through the folding mechanism, constructed and arranged to fold the projecting ends of the wrapper against the sides of the superposed sticks. After the wrapper has been closed the packages are discharged into a stacker and are successively stacked therein.

In carrying out the invention the sets of superposed sticks and wrapper are fed first into a pocket which causes the wrapper to be folded across the top, rear end and bottom of the sets of pairs and the pocket is then moved to another position in which the projecting ends of the wrapper are closed around the advance end of the package and from which position the package

is discharged into the folding mechanism by means of which the ends of the wrapper are folded.

Further details of the invention will appear from the following description.

Gum stick feed mechanism

In the particular embodiment of the invention illustrated and especially shown in Figs. 1, 2 and 7, the sticks of gum which are preferably wrapped are superposed in the hopper H. From the hopper H the sticks are discharged in pairs by means of a reciprocatable plunger 30 connected to a slide block 31 mounted in a guideway 32 and reciprocated by a link 33. The link is connected at its rear end to the upper end of a lever 34 mounted on a fixed pivot 35 and pivoted at 36 to a link 37. Link 37 is connected at its opposite end to a pin 38 carried by an eccentric 39 mounted on a shaft 40. Shaft 40 has secured thereto a gear 41 which meshes with a gear 42 mounted on the main drive shaft 43. Shaft 43 is driven from any suitable source of power through clutch mechanism indicated at 45.

As the plunger 30 is reciprocated each forward movement thereof will discharge the two lower sticks from the stack in the hopper H onto a table 46 and between guide members 47 and 48 which form a channel for receiving the sticks.

The sticks are fed along the table or support 46 by means of a pair of feed bars 50 and 51 having upwardly extending feed fingers 52. The table 46 is longitudinally slotted to permit the fingers to project upwardly and engage behind the set of sticks as they are fed into position for engagement by the fingers by the reciprocating plunger 30.

The bars 50 and 51 are carried by vertically extending bars 53 and 54 which are connected by a cross member 55. The member 55 is connected to a vertical post or bar 56 which is vertically reciprocatable in a block 57 which in turn is slidably mounted on a horizontal bar 58 (Fig. 2A). The vertical post 56 has secured to its lower end a roller 59 which is mounted in a horizontal guideway 60 vertically reciprocatable on a post 61. The guideway is reciprocated by means of a link 62 which is connected at 63 to an arm 64 mounted on a pivot 65. This arm 64 has connected thereto an arm 66 so that the arms 64 and 66 form a bell crank lever about the axis of the pivot 65. The upper end of the arm 66 is connected at 67 to a pitman 68. One end of the pitman 68 is connected at 69 to a roller 70 which is positioned in the groove of a cam 71 on a shaft 92.

An eccentric 68' at the forward end of the shaft 92 has the link 72 connected to a lever 73 mounted on a fixed pivot 74 and having pivoted to its upper end a link 75 which is pivoted at 76 to the reciprocatable block 57.

Thus, by the cam operation of the links 68 and eccentric 68' the bars 50 and 51 will be raised and lowered and also moved longitudinally to successively feed the pairs of sticks of gum forwardly through the channels 47 and 48. It will be understood without further description that the plunger 30 is so timed as to position five pairs of sticks on the table 46 between the channels 47 and 48 and in the path of movement of the right hand fingers 52 (viewing Fig. 2). These fingers first engage the grouped pairs of sticks and feed them forwardly and are thereafter retracted. On the next movement of the bars the sticks are engaged by the second set of fingers from the left

viewing Fig. 2 and are in this manner intermittently fed through the channels.

After the mechanism just described has fed a plurality of pairs of sticks forwardly, and in the embodiment of the invention shown, five pairs are fed, to the forward end of the table 46 these five pairs of sticks are fed at right angles to their first path of movement into a pocket P by means of a reciprocatable plunger or plunger plate 80. In this connection attention is directed particularly to Figs. 1, 5, 9, 10 and 11. The plate 80 is carried by a bracket 81 to which is connected a link 82 which is connected to a lever 83 (Figs. 5 and 10). Lever 83 is mounted on a fixed pivot 84 and is operated by a pitman 85 having on its rear end a yoke 86 which straddles a shaft 87 (Fig. 9). The yoke 86 carries a roller 88 which is positioned in a cam groove in a cam 89 mounted on the shaft 87.

The shaft 87 has secured thereto a bevel gear 90 which meshes with a bevel gear 91 carried by the shaft 40'. Shaft 40' is driven from shaft 43 by spur gears shown in Fig. 7.

The cam 71 and eccentric 68' which control the operation of the feed bars 50 and 51 is mounted on a shaft 92 which is connected by a bevel gear connection 93, 94 with the shaft 87.

The shafts are so timed and the cams are so designed that the feed plate or plunger 80 will be operated to feed five sets of superposed pairs of sticks of gum from the table 46 into the pocket P after these five sets have been assembled in position for engagement by the plate or plunger 80.

Paper feed

Before describing the folding operation in the pocket P or the movements of this pocket from receiving to discharge position the paper feeding mechanism for feeding the paper strip or wrapper into the path of movement of the five pairs of sticks as these sticks are pushed into the pocket by the plunger 80, will be described. In this connection attention is directed particularly to Figs. 1, 5, 7, 8 and 11. The paper strip is carried by a supply roll S mounted on a roll. From the bracket 95 the strip is led beneath an idler roll 96 and through an electric eye regulating device shown at 97, 98 to the paper feeding mechanism. The electric eye mechanism which will be described later, is provided for the purpose of regulating the feed of the strip in order to correctly cut the wrapper so that the printing will be properly positioned on the wrapper. The wrapper which is shown in plan view in Fig. 6 is provided with printed matter shown at 99 and it is essential for the proper appearance of the wrapper on the package that this printed matter be correctly positioned.

The strip 100 from the supply roll S first passes between a pair of rolls 101 and 102, the roll 101 having a pair of knife blades 103 which slit the wrapper as shown at 104 in Fig. 6. After the strip passes around the roll 102 it is led between a pair of feed rolls 105, 106 and downwardly between guide members 107 and between a stationary knife blade 108 and a rotary knife blade 109, the latter blade being carried by a knife roll 110. The cutting mechanism just described is carried by a bracket 111 which carries a gear 112 which meshes with a rack 113 formed on the vertical post 114. By rotating the gear 112 manually the cutting mechanism and bracket 111 can be vertically adjusted.

From the cutting mechanism the severed strip 75 passes downwardly between a pair of feed rolls

115, 116 and into the path of movement of the five pairs of sticks which are fed by the plunger plate 80. The wrapper extends downwardly into a vertical slot 117 and is fed into this slot at the proper time in the sequence of operation of the machine to be engaged by the five sets of sticks of gum as these sticks are fed by the plate 80.

The feed rolls 115 and 116 are carried by a bracket 118 which has mounted thereon a gear 119 which engages teeth 120 in the vertical post 114. Thus, these feed rolls are vertically adjusted with the post and also relative to the post.

The driving connections for the paper feeding mechanism will now be described. The left hand end of the shaft 87, viewing Fig. 1, has connected thereto a bevel gear 125 which meshes with a bevel gear 126 carried by a shaft 127. This shaft has secured thereto a bevel gear 128 which meshes with a bevel gear 129 secured to a vertical shaft 130. (See Figs. 1, 2 and 5.)

Shaft 130 has secured thereto a gear 131 which meshes with a gear 132 on a parallel shaft 133. Shaft 133 has also secured thereto a gear 134 which meshes with a gear 135 carried by a sleeve 136 rotatably mounted on the shaft 130. Sleeve 136 has also secured thereto a gear 137 which meshes with a gear 138 which is mounted on a shaft 139 which carries the feed roll 115.

The shaft 130 has also secured thereto a bevel gear 140 which meshes with a bevel gear 141 carried by a shaft 142 which also has secured thereto the roll 110 which carries the rotary knife 109.

Shaft 142 has also mounted thereon a gear 143 which meshes with an idler gear 144 which in turn drives a gear 145 mounted on shaft 146. This shaft carries a spider 147 having planet gears 148 which mesh with a pinion gear 149 fixed to a shaft 150 on which feed roll 105 is mounted. Planet gears 148 also mesh with a ring gear 151 carried by a ring gear housing 151A on which is fixed a worm wheel 152, (see Figs. 3 and 4).

A worm 153 meshes with the worm wheel 152, the worm being carried by a shaft 154 (Figs. 17, 18 and 19). Shaft 154 has secured thereto a ratchet wheel 155 which is engaged by a pawl 156 carried by an arm 157 pivotally mounted on the shaft 154. A holding pawl 156' mounted on a fixed arm 157' also engages the ratchet wheel. The arm 157 has secured thereto and extending therefrom on the opposite side of the axis of the shaft 154 a bracket 158 to which is pivoted a bell crank lever comprising arms 159 and 160. The arm 159 is positioned in the path of movement of an adjustable screw 161 carried by an arm 162 fixed to a reciprocatable or slideable rod 163. The arm 159 is held in engagement with the screw 161 by means of a spring 164 which engages the arm 160.

One end of the rod 163 is pivotally connected at 170 to an armature arm 171 mounted on a pivot 172 and controllable by a solenoid 173. As the solenoid is energized in the manner herein-after described the armature 171 will be moved to the left or in an anticlockwise direction about its pivot 172, thus causing the rod 163 to move to the left and in turn causing the screw 161 to move bell crank lever 159, 160 about its pivot in a clockwise direction from the dotted line position shown in Fig. 17 to the full line position shown therein.

The arm 160 has secured to its end a plate 175 having a knife edge 176 at its upper end. When the solenoid is energized and the bell crank lever 159, 160 is moved in a clockwise direction to the

position shown in full lines in Figs. 17 and 20, the plate 175 and the knife edge 176 will be positioned in the path of movement of the lower end of a notched screw 180 carried by an arm 181 mounted on a pivot 182. The arm 181 is connected to a sleeve 183 to which is also connected a downwardly extending arm 184 having a roller 185 which engages a cam 186 carried by a shaft 187. Shaft 187 has secured thereto a gear 188 which meshes with a gear 145 carried by the shaft 146.

Roller 185 is held in engagement with the cam 186 by means of the spring 195 which engages the arm 184. The arm 157 is held in its position of rest by means of a spring 196.

The arm 181 and screw 180 carried thereby are vertically oscillated by the cam 186, but unless the solenoid 173 is energized to cause the rod 163 to move the pin 161 and thus swing the bell crank lever 159 and 160 to a position in which the knife edge 176 on the plate 175 will be positioned in the path of movement of the notched lower end of the screw 180, the operation of the arm 181 will be ineffective. However, when these two parts are disposed in alignment, as shown in Fig. 20, the downward movement of the arm 181 will cause the arm 157 to move in a clockwise direction and the pawl 156 will engage the ratchet wheel 155 and cause this wheel to rotate the shaft 154, thus turning the worm 153, the worm wheel 152. As the worm wheel is rotated the ring gear 151 will also be rotated and through the planet gears which engage the pinion 149 shaft 146 and the spider 147 will be rotated through an increment of movement. The spider 147 is carried by a shaft 146 and the feed roll 105 is mounted on shaft 150. The photoelectric cell circuit for controlling the energizing of the solenoid 173 will be later described.

The sticks of gum disposed at the end of the table 46 are fed into the pocket P (Fig. 11) over the top of a block 200 by means of the feed plate or plunger 80. In moving into the pocket 45 they engage the wrapper which is disposed in the path of movement thereof and the wrapper is forced into the pocket and around the advance end, top and bottom of the articles to be wrapped. The two ends of the wrapper project beyond the open end of the pocket, as shown in Fig. 23.

A bracket 201 is mounted above the pocket P on the vertical post 202 on which the bracket 203 carrying the pocket is also mounted. These two brackets are vertically reciprocatable or movable in a manner which will now be described.

The bracket 201 has mounted on the outer end thereof a roller 204 which is carried by a spindle 205. The roller receives adhesive or moistening material for the wrapper from a wick 206 which is adapted to engage the roller. A plate 207 is also carried by the bracket adjacent the roller.

Shaft 205 is driven from shaft 139 through gears 218, 219 which drive shaft 208 which in turn is connected through a universal joint 209A to the shaft 205.

The shaft 101' on which the knife blades 163 are carried is driven from the shaft 146. An idler gear 102' meshes with gear 145 on shaft 146 and drives the gear 103' mounted on the knife blade shaft 101' (Fig. 5).

When the ends of the wrapper project from the pocket P the bracket 201 is lowered, causing

the liquid to engage the outer surface of the upper flap or end and to render this surface adhesive. The downward movement of the plate also folds this upper projecting end downwardly. After this operation is completed the pocket P moves downwardly in a manner hereinafter described, causing the lower projecting end to be folded upwardly against the folded upper end, the lower projecting end being folded by engagement with an edge 268 formed on the block 260. This block encloses electric heating coils which engage the outer surface of the folded ends of the wrapper, drying and sealing the ends of the wrapper.

The bracket 261 is vertically moved in the manner just described by means of a link 210 which is connected to a bell crank lever 211, 212, the arm 212 of the bell crank lever being pivoted at 213 to a link 214 (Fig. 11). The lower end of the link 214 is bifurcated or has connected thereto a bifurcated yoke 215 which straddles the shaft 87 and carries a roller 216 which is actuated by a cam 217 fixed to the shaft 87 (Fig. 9).

The pocket bracket 263 has connected thereto a link 220 which is pivoted to an arm 221 secured to a shaft 222. The shaft 222 has secured thereto an arm 223 to which is pivoted at 224 a pitman 225 which has a roller 226 operated by a cam 227 mounted on the shaft 87.

The cam 227 is so designed that when the load has been pushed with the wrapper into the pocket P and the upper projecting end has been moistened and lowered or folded, the pocket is moved downwardly causing the lower projecting end to fold over the other down-turned end moving the overlapping ends over the heater and thus sealing the folded ends of the wrapper. The pocket moves downwardly to a position opposite a receiving platform 230 which receives the package from the pocket in the following manner:

The feeding means for ejecting the package from the pocket is particularly illustrated in Figs. 1, 9, 10 and 11. From Fig. 9 it will be seen that a plate 231 is disposed in the pocket P at the back end thereof, this plate being carried by a pair of posts or pins 232, 232. The rear ends of the pins 232 are provided with heads 233. These heads are disposed between plates 234, 235 carried by a bracket 236, the plates being inclined toward each other, as shown in Fig. 10. The pins 232 extend through vertical slots in the plate 234.

After the pocket P has been lowered in the manner hereinbefore described, the bracket 236 is moved to the left in the following manner: The bracket has connected to the upper end thereof a rearwardly extending arm 237 which is pivoted at 238 and 239 to parallel links 240 and 241. These links are mounted on fixed pivots 242 and 243 at the lower ends thereof. The link 240 is pivotally connected at 244 to a yoke 245 which straddles shaft 87 and has a roller 246 which engages a cam 247 mounted on the shaft 87 and designed to reciprocate the bracket 236 and pins 232 actuated thereby at the proper sequence in the operation of the machine to eject the wrapped articles from the pocket P onto the table 230. The table 230 is provided at the side edges thereof with plates 250 having fold grooves 251 of the usual construction designed to fold the projecting side edges of the wrapper inwardly and to seal these projecting edges, suitable drying plates being provided to dry the sealed ends.

In order to render the projecting ends adhesive there are provided at the sides of the sup-

porting plate or table 230 moistening wicks 255 which are carried by brackets 256 to which is connected a tank 257 for holding the moistening liquid. The wicks extend downwardly into the tank, as shown in Fig. 24. The tank 257 has extending downwardly therefrom lugs 258 carrying a pin 259 which is positioned in a forked arm 260 carried by the spindle 84. As the arm 83 oscillates the spindle 84 the tank 257 and the brackets 256 and wicks 255 will be raised and lowered so that the moistening liquid or adhesive will be applied to the inner surfaces of the lower side flaps 261, 261 at the desired period in the sequence of operation of the machine, as shown in Fig. 24.

It will be noted that the adhesive is applied when the flaps 261 have been partially folded and it will be understood that the folding slots in the side plates 250 will fold the upper flaps downwardly and then will fold the lower flaps upwardly in the usual manner. From the folding slots the packages pass between heating plates which complete the sealing operation.

Feed discharger, conveyor and stacking mechanism

The packages discharged from the pocket P to the support or table 230 are fed along this table and through the folding mechanism which completes the folding operation by means of a plurality of feed bars or members 265 which are carried by an endless conveyor or chain 266 which extends around a sprocket wheel 267, a guide wheel 268 and a guide member 269. (See Figs. 10 and 11.)

The sprocket wheel 267 is driven intermittently in the following manner: The sprocket wheel 267 is rotatably mounted on a shaft 270 on which is fixed a gear 271 which is engaged by teeth 272 formed in a rack bar 273. The rack bar is held in engagement with the gear 271 by means of a roller 274 mounted on a fixed bracket 275. The rack bar 273 extends rearwardly and has secured to its rear end an eccentric strap 276 which is mounted on an eccentric 277 carried by the shaft 87.

As the shaft 87 and eccentric 277 are rotated the rack bar 273 will be reciprocated. The shaft 270 has secured thereto an arm or bracket 278 on which is mounted a pawl 279 which engages a ratchet wheel 280 to which is fixed the sprocket wheel 267 (Fig. 13A). The pawl 279 under the operation of the shaft 270 will cause this ratchet wheel to be rotated as the rack bar 273 moves to the left viewing Fig. 10, thus causing the sprocket wheel to operate the feed chain 266 through one direction of its movement.

The wrapped packages are fed through the folding mechanism by the feeding members 265 by the movements of the feed chain and after the folding operations have been completed the packages are fed beneath a plate 280 which is positioned above the curved discharge end 281 of the table 230. (See Figs. 5, 8, 10 and 12.) From the end 281 the packages are discharged into stacking mechanism which is constructed and operated in the following manner: A reciprocatable plate 282 (see Fig. 5) is carried by a bracket 283 to which are pivoted parallel links 284 and 285. The link 285 forms one arm of a bell crank lever, the other arm 286 of which is pivoted to a link 287 which in turn is pivoted on a pin 288 carried by a disk 289 mounted on a shaft 290. This shaft also has mounted thereon a gear 291 which meshes with a gear 292. Gear 292 is carried by a sleeve 293 mounted on a shaft 270 (Figs. 12 and 13). This sleeve also has secured thereto a ratchet

wheel 294 which is engaged by a pawl 295 carried by a bracket 296 having a hub 297 fixed to the shaft 270. This pawl and ratchet mechanism operates in a manner similar to the pawl and ratchet drive for the sprocket wheel 267, but the pawl and ratchet drive for the sprocket wheel 267 operates during the movement of the rack bar 273 in one direction and the pawl and ratchet drive for the stacking mechanism operates during the movement of the rack bar in the opposite direction. These connections are so arranged that the plate 282 will be disposed in its lower position, as shown in Fig. 5, when a package is discharged between the plate 280 and the curved end 281 of the support or table 230. Thereupon the pawl and ratchet drive for the stacking mechanism will move the plate 282 upwardly forcing the package upwardly between a pair of pivoted hook-shaped members 300 and 301 (see Fig. 14). These members have converging faces 302 on the outer surfaces of the hooks and as the packages move upwardly the members 300 and 301 are spread or move away from each other to permit the packages to pass between the members 300 and 301, as clearly shown in Fig. 14. The members 300 and 301 have arms 303 and 304 at their upper ends, these arms being connected to the members through spindles 305. The arms 303 and 304 are engaged by a spring 306 which pulls the arms upwardly and holds the lower ends of the members 301 and 300 inwardly, as shown in Fig. 14.

As hereinbefore stated, the feed mechanism for the paper is regulated by photoelectric control mechanism designated on Fig. 5 as 97, 98. Fig. 25 illustrates diagrammatically and simply a circuit for the photoelectric mechanism. The photo tube 97, as shown in Fig. 25, is connected by wires 310 and 311 to wires 312 and 313 which in turn are connected to wires 314 and 315. The wires 314 and 315 are connected to terminals or contact members 316 and 317. The circuit through the members 316 and 317 is controlled by a plate 318 which is mounted to rotate with the shaft 127. This shaft has rings 320 and 321 (Figs. 15 and 16) on which the contact members 316 and 317 rest during the major operation of the revolution of the shaft, but the rings 320 and 321 are not electrically connected together. Thus, the circuit is completed through the members 316 and 317 only when these members are in engagement with the plate 318. The circuit from the plate 318 is conducted through wires 322 and 323 to the solenoid 173. As hereinbefore explained, when the solenoid circuit is closed the solenoid is energized and actuates the feed correction mechanism. The extent of rotation of the feed roller by this correction mechanism is determined by adjustment of the screws 161 and 181 and also it should be noted that the worm 153 can be rotated by a handle 325 mounted on the end of the spindle 154.

The shaft 127 and the contact plate 318 carried thereby are so operated that the circuit through the photoelectric cell will be closed only when a shaded portion 326 of the wrapper 99 is disposed in the range of the cell. When the beam of the cell strikes the shaded portion 326 the position of the feed roll 105 will be corrected if the wrapper strip is being incorrectly fed.

In Fig. 25 there is illustrated a suitable control box B for the photoelectric cell mechanism, the main line for supplying power for this mechanism being designated at 330 and 331.

Summary of operation

The operation of the machine may be briefly summarized as follows: The sticks of gum are

ejected or fed from the hopper H in pairs by the reciprocating plunger 30 to the supporting table 46. When five pairs have been fed by the plunger bars 50 and 51 and fingers 52 carried thereby are operated to feed this group of ten sticks or five pairs intermittently along the table 46 to successive positions until the group is fed to the end of the table in a position to be engaged by the feeding plate 80 which feeds the group or set of ten sticks into the pocket P. The wrapper is disposed in the path of movement of the group of ten sticks and is fed into the pocket with the load and is thereupon positioned around the end, top and bottom of the articles, the ends of the wrapper projecting beyond the outer end of the pocket, as shown in Fig. 23. The moistening roll 204 then descends and moistens the outer surface of the upper projecting end and folds it downwardly, whereupon the pocket and load carried thereby is lowered from the position shown in Figs. 11 and 23 to a position opposite the receiving end of the table 230.

The paper from the supply roll S is fed past the photoelectric cell mechanism, is slit by the blades 103 and fed downwardly between rolls 105 and 106 to the cutting mechanism 108, 109 which severs the strip to the proper length. From this mechanism the wrapper is fed downwardly by the feed rolls 115 and 116 to a position in the path of movement of the load as the load is fed by the feeding plate 80 into the pocket.

The electric eye operates in the manner hereinbefore described to rotate the ring gear 151 and through the planetary gearing to rotate the feed roll 105 in the proper direction to correct the position of the wrapper strip and properly feed the strip to the wrapping mechanism.

After the pocket P has been depressed to a position opposite table 230 the load is ejected from the pocket by the actuation of the pins 232 and the package is fed through the final wrapping mechanism by the feeding members 265 carried by the chain 266. During this movement the laterally projecting ends 261, 261 are moistened or rendered adhesive and folded downwardly and the lower projecting edges are folded upwardly to close the package.

The completed package is discharged by the feeding members 265 to stacking mechanism, each package being received by the plate 282 and fed upwardly by this plate to a position between the hook-shaped retaining members 300, 301.

Although one specific embodiment of the invention has been particularly shown and described it will be understood that the invention is capable of modification and that changes in the construction and in the arrangement of the various co-operating parts may be made without departing from the spirit or scope of the invention, as expressed in the following claims.

What I claim is:

1. In a wrapping machine, a pocket, means for moving a plurality of articles and a wrapper into said pocket with the ends of the wrapper projecting from the pocket, a vertically reciprocating roller adjacent the pocket arranged to apply liquid to one of the projecting ends of the wrapper and to fold said end of the wrapper, means for moving the pocket and means engageable with the other projecting end of the wrapper as the pocket is moved, for folding said other end against said first mentioned folded end.
2. In a wrapping machine, a pocket, means for moving a plurality of articles and a wrapper into said pocket with the ends of the wrapper pro-

jecting from the pocket, a vertically reciprocating roller adjacent the pocket arranged to apply liquid to one of the projecting ends of the wrapper and to fold said end of the wrapper, means for moving the pocket and means engageable with the other projecting end of the wrapper as the pocket is moved, for folding, heating and pressing said other end against said first mentioned folded end.

3. In a wrapping machine, a pocket, means for moving a plurality of articles and a wrapper into said pocket with the ends of the wrapper projecting from the pocket one above the other, a vertically reciprocating roller adjacent the pocket arranged to apply liquid to the upper projecting end of the wrapper and to fold said upper end of the wrapper downwardly, means for moving the pocket and means engageable with the lower projecting end of the wrapper as the pocket is moved, for folding said lower end upwardly against said upper folded end.

4. In a wrapping machine, a pocket, means for moving a plurality of articles and a wrapper into said pocket with the ends of the wrapper projecting from the pocket one above the other, a vertically reciprocating roller adjacent the pocket arranged to apply liquid to the upper projecting end of the wrapper and to fold said upper end of the wrapper downwardly, means for moving the pocket and means engageable with the lower projecting end of the wrapper as the pocket is moved, for folding, heating and pressing said lower end against said upper end.

5. In a wrapping machine, a pocket, means for feeding articles and wrappers horizontally into said pocket, with the ends of the wrappers projecting from the pocket one above the other, a vertically reciprocating roller adjacent the pocket arranged to apply liquid to the upper projecting ends of the wrappers and to fold said upper ends downwardly, means for moving the pocket downwardly and stationary means engageable with the lower ends of the wrappers as the pocket is moved for folding said lower ends upwardly against said folded upper ends.
- 10 6. In a wrapping machine, a pocket, means for moving articles and wrappers horizontally into said pocket, with the ends of the wrappers projecting from the pocket one above the other, a vertically reciprocating roller adjacent the pocket arranged to apply liquid to the upper projecting ends of the wrappers and to fold said upper ends downwardly, means for moving the pocket downwardly to a second level, stationary means engageable with the lower ends of the wrappers during said movement of the pocket for folding said lower ends upwardly against the upper folded ends, means for discharging the articles and wrappers from the pocket at said second level, means for feeding the articles and wrappers at said second level and means for completing the wrapping operation during said last mentioned feeding movement.
